CLAIM

We claim the ornamental design for a knee pad, as shown and described.

DESCRIPTION

FIG. 1 is a front view of a first embodiment of the knee pad; FIG. 2 is a plan view of the first embodiment of the knee pad;

FIG. 3 is a side view of the first embodiment of the knee pad; FIG. 4 is a rear view of the first embodiment of the knee pad; FIG. 5 is an inverted plan view of the first embodiment of the knee pad;

FIG. 6 is a right side view of the first embodiment of the knee pad;

FIG. 7 is a perspective view of the first embodiment of the knee pad;

FIG. 8 is a perspective view illustrating the first embodiment of the knee pad in an "in use" configuration;

FIG. 9 is a front view of the second embodiment of the knee pad;

FIG. 10 is a plan view of the second embodiment of the knee pad;

FIG. 11 is a left side view of the second embodiment of the knee pad;

FIG. 12 is a rear view of the second embodiment of the knee pad;

FIG. 13 is an inverted plan view of the second embodiment of the knee pad;

FIG. 14 is a right side view of the second embodiment of the knee pad;

FIG. 15 is a perspective view of the second embodiment of the knee pad; and,

FIG. 16 is a perspective view of the second embodiment of the knee pad in an "in use" configuration.
